UNITED STATES PATENT OFFICE.

CANDACE T. WHEELER, OF NEW YORK, N. Y.

FABRIC FOR NEEDLE-WOVEN TAPESTRIES.

SPECIFICATION forming part of Letters Patent No. 271,174, dated January 23, 1883.
Application filed March 27, 1882. (No model.) Patented in England March 14, 1882, No. 1,233.

To all whom it may concern:

Be it known that I, CANDACE T. WHEELER, a citizen of the United States, residing in the city, county, and State of New York, have invented a new and useful Fabric for Needle-Woven Tapestries; and I do hereby declare the following to be a sufficiently full, clear, and exact description thereof to enable others skilled in the art to make and use the said invention.

The object of this invention is to provide a material to form a ground or support for needle-woven designs capable of receiving such designs between the woven threads and exhibiting them as apparently woven with the fabric in the loom, although actually inserted by hand with a needle or equivalent implement. A fabric of this kind is shown with embroidery-threads combined therewith in Letters Patent granted to me November 28, 1882, and numbered 268,332, to which reference may be had.

The nature of my invention consists in a fabric having a soft or compressible woof on its face displayed between fine warp-threads, which fine warp-threads pass alternately to the face and back of the fabric and bind the soft woof-threads over a series of intervening warp-threads, and also hold the woof-threads of the back (which may be of the same or of different material from the front woof-threads) against the intervening warp-threads. The proportions of the back woof-threads as compared with the woof-threads of the face are such that the back woof-threads of the fabric are large and in close contact with each other, while the woof-threads of the face are smaller and leave spaces or interstices between them susceptible of receiving ornamental threads, to be introduced with a needle by hand, without such ornamental threads protruding appreciably above the surface of the woven fabric.

I will now proceed to fully describe this invention particularly and exactly, referring in so doing to the drawings annexed and the letters of reference marked thereon.

Figure 1 shows a plan of the face or "right" side of the fabric or woven cloth; Fig. 2, a plan of the back or "wrong" side; Fig. 3, a section lengthwise on the line X-X in Figs. 1 and 2; Fig. 4, a section lengthwise on the line Y-Y in Figs. 1 and 2, and Fig. 5 shows a trans-

verse section on the line Z-Z in Fig. 1. These several figures are drawn on an enlarged scale for the greater facility of distinguishing the several threads. Fig. 6 shows the working part of a loom adapted to weave such fabric, one side frame of the loom being omitted, so as to show the position of the working parts and the several series of threads which enter into the fabric.

The same letters of reference apply to the same parts in the several figures.

A and A' represent the soft or compressible woof-threads of the face; B and B', the woof-threads of the back; C, the tight or straight warp-threads; D and D', the serpentine or binding threads of the warp. The threads C, forming the straight warp, pass in a straight line between the face woof-threads, A and A', and the back woof-threads, B and B', as shown in Fig. 4. The woof-threads A of the face and the woof-threads B of the back are held against the straight warp-threads C by the serpentine warp-threads D', and the woof-threads A' of the face and B' of the back are held against the straight warp-threads C by the warp-threads D, as shown in Fig. 3, the said warp-threads D and D' passing between the straight warp-threads C. The straight warp-threads C hold the woof-threads close to each other in the direction of the length of the fabric, and impart firmness in that direction, and give an effect of fullness to the woof-threads where they appear between the serpentine threads D and D'.

To produce this cloth a loom with two shuttles is used, one shuttle introducing the upper or face woof-threads and the other the lower or back woof-threads. Two beams are used, one supplying the straight warp and the other the serpentine warp threads, such looms as are used to produce the figured fabrics employed for upholstering, in which the figure is formed from the woof-threads, and not by the warp-threads, being suitable for the purpose, when the jacquard or figuring apparatus connected with the treadles or harness is detached and the heddles operated only by the treadles and cams on the shaft.

The essential working parts of a loom adapted to weave this fabric are shown in Fig. 6, in which D² represents the beam upon which the straight warp-threads C are wound; D³, the

beam on which the serpentine or binding threads of warp are wound; E, the cloth-roll; F, the lathe or sley carrying the reed F', and reciprocated by the crank G' on the driving-shaft G by the connecting-rod G². H is the harness, consisting of two series of treadles, H' and H², connected above by straps H³, passing over rollers H⁴, and connected below to and operated by treadles J and J', worked by cams K and K' on the cam-shaft L, which is driven by spur-gear wheels M and N, so as to make one revolution in the same time as the main driving or crank shaft makes two revolutions. O and O' are shuttles operated by a cam, P, on the shaft L, moving levers Q and Q', the upper ends of which propel the shuttles O and O'. The levers Q and Q' reciprocate upon fulcrums Q³ and Q⁴ laterally, or in a direction at right angles to the warp-threads, when the cam P strikes the lever-arm Q². The connection between the upper ends of the levers Q and Q' is effected in the usual manner of connecting the picker-staff by a strap, Q⁵, having one end fastened to a slide in the shuttle-box and the other end to the upper end of the lever Q or Q'. A second cam placed on the shaft L is employed to operate the lever or picker-staff of the opposite side of the loom, which cam has its boss or hub, as shown in the drawings, coincident with the hub of the cam P, and the projecting finger (marked P²), which is the only portion visible in the drawings, is set diametrically opposite on the shaft L to the finger of the cam P.

The warp C on the beam D² is held tight by means of a strap, R, wrapped around the beam D², tightened by a weight, S. A similar strap, R', wrapping upon the beam D³ and tightened by a weight, S', tightens the warps D and D' not as tightly as the warp C.

The necessity for placing the warps D and D' on a separate beam from that carrying the warp C arises from the fact that the binding or serpentine warps D and D' are longer than the straight warps C, and must be supplied faster.

The cloth as woven is wound upon the cloth-roll F by means of a ratchet-wheel and pawl in the manner usually practiced in ordinary looms. The usual bars and rails, T and U, support the warps and cloth.

The operation of the loom in producing the fabric is as follows: The warp D' being raised and warp D depressed, the shuttle O passes between the warp C and the warp D', and at the same time the shuttle O' passes between the warp C and the warp D, leaving woof-threads A and A' in their track, and the lathe and reed push the woof-threads thus placed backward toward the cloth-roll. The warp D' is next depressed and the warp D raised, and the shuttles O and O' retrace their paths, leaving in them the woof-threads A and A', and the reed and lathe press them home toward the woof-threads previously deposited, and these operations are repeated in the same

order, and the fabric is thus formed, the cloth-roll being turned slowly, so as to wind the fabric on it as it is produced, and the beams D² and D³ unwinding the warp-threads C and D and D' as they are required. The woof-threads of the face are of yielding material and smaller than those of the back, which are tightly woven as compared with the face. The woof-threads are sufficiently compressible to permit of the introduction of threads under the loops of the serpentine threads D and D' and over the face of the woof-threads A, so that by either wholly or partially covering these woof-threads with ornamental threads, parallel thereto, thus introduced, designs can be produced which, not being perceptibly prominent and being crossed at regular intervals by the loops of the threads D and D', appear as though they were a component part of the loom-woven fabric.

The loom described in this specification does not form any portion of this invention, such description being introduced solely for the purpose of showing the manner in which the fabric that constitutes my invention is produced.

I am aware that fabrics having figuring woof-threads held against straight central warp-threads by binding or serpentine warp-threads have been made. In such fabrics the same woof-threads appear at intervals in the face and back, and they are not adapted to the uses for which my invention is designed—first, because they do not present the requisite interstices of the face to receive ornamental threads without protrusion thereof; second, because the difference in color or material of the two or more sets of figuring woof-threads defeats the effect of uniform ground for artistic effect, and third, because the points where the figuring woof-threads pass from the front to the back of the fabric change the arrangement of crossing warp-threads so as to interrupt the regular intervals or spaces between such warp-threads on the face. Such fabrics containing figuring woof-threads are not a part of my invention, and are hereby disclaimed; but

What I claim as my invention is—

A new article of manufacture consisting essentially of a plain woven fabric, canvas or cloth, having a closely-woven back of thick woof-threads and an open or loosely-woven face of thinner woof-threads, with interstices between the face woof-threads adapted to receive ornamental threads without appreciable protrusion, the said back and face woof-threads being held by a double series of crossing or binding warp-threads passing alternately from the face to the back of the fabric, and holding the woof-threads both of the face and back to an intermediate series of straight warp-threads, substantially as shown and described.

CANDACE T. WHEELER.
